UNITED STATES PATENT OFFICE

JOSEPH FOLK, OF LA PORTE, INDIANA, ASSIGNOR TO U. S. SLICING MACHINE COMPANY, OF LA PORTE, INDIANA, A CORPORATION OF INDIANA

SLICE COLLECTOR FOR SLICING MACHINES

Application filed July 17, 1926. Serial No. 123,044.

This invention relates to means for collecting and assembling the slices as they are formed by a machine for slicing meat or other material, and has for its object the provision of such a device which shall be of improved construction and operation, which shall be simple and economical to manufacture, which shall require a minimum amount of power to operate and which shall consist of but few parts so arranged that the parts will stand a long period of wear without interfering with their operation.

Another object of this invention is to provide a deflector which also acts as a stacker to stack the slices on a receiving surface as they are cut by the slicing knife, it being preferable to arrange the receiving surface below the supporting surface of the table upon which the substance is supported while being sliced.

The invention is exemplified in the combination and arrangement of parts shown in the accompanying drawings and described in the following specification, and it is more particularly pointed out in the appended claims.

In the drawings—

Fig. 1 is a front elevation of a slicing machine showing one embodiment of the present invention applied thereto;

Fig. 2 is a top plan view of the mechanism shown in Fig. 1 with the slicing knife shown in section;

Fig. 3 is a vertical section substantially on line 3—3 of Fig. 2;

Fig. 4 is a horizontal section on line 4—4 of Fig. 3;

Fig. 5 is a horizontal section on line 5—5 of Fig. 3;

Fig. 6 is a horizontal section on line 6—6 of Fig. 3; and

Fig. 7 is a vertical section on line 7—7 of Fig. 2.

The numeral 10 designates the frame of a slicing machine having the usual reciprocating table 11 mounted on a guide bar 12 and movable past a rotary slicing knife 13 for presenting the material to the knife to be sliced. Projecting forwardly from the base

10 is a bracket 15 having a perforation 16

therein for holding bearing bushings 17 and 18 which are fixed therein. A spider 19 is journaled on the upwardly projecting portion of the bushing 18 while the bushing 17 is journaled in a bracket 20 secured to the spider 19 by screws 21 and extending downwardly below the lower face of the bracket 15. The bracket 15 is provided with a recess for receiving a ratchet wheel 22 interposed between the ends of the bushings 17 and 18. 55 A spring detent 23 engages the teeth of the ratchet wheel 22 to hold it against rotation in one direction and a second pawl 24 is carried by a sleeve 25 mounted in the bracket 20 and engages the ratchet wheel 22 to rotate 60 the ratchet wheel when the spider 19 is rotated in a counter-clockwise direction, as viewed in Fig. 4. A screw 26 extends through the openings in the bushings 17 and 18 and is provided with a flange 27 at its lower end 65 to limit upward movement of the screw. A ball 28 is carried in a sleeve 29 in the ratchet wheel 22 and engages the threads of the screw 26. The ball 28 is held in yielding contact with the threads of the screw 26 by a 70 spring 30. The spider 19 is connected to the reciprocating table 11 by means of a connecting rod 31 having one end pivoted to the spider at 32 and the opposite end carried by a downwardly projecting pivot pin 33 75 mounted on a bracket 34 secured to the end of the reciprocating table 11 by screws 35. It will be apparent from Fig. 2 that reciprocation of the table 11 will be transmitted to the spider 19 which will reciprocate about 80 the axis of the screw 26.

The edge of the spider 19 adjacent the machine frame is curved about the axis of the screw 26 and is provided with an upright plate 36 which extends upwardly to a position just below the edge of the reciprocating table 11. The ends of the plate 36 are continued forwardly in straight portions 37 and 38. The upper end of the screw 26 carries a horizontal plate 39 fixed to the screw 26 and shaped to fit within the contour of the plate 36. The shape of the plate 39 fitting within the plate 36 constrains the screw 26 to oscillate in unison with the spider 19. It will be seen from Figs. 2 and 4 that when the table 100

11 moves forwardly on a cutting stroke the spider 19 will be moved in a counter-clockwise direction and will carry the ratchet 22 with it, the ratchet teeth moving idly over the detent 23. There will be no relative movement between the ratchet wheel and screw 26 at this time since they all travel in unison with one another. During the return movement of the feed table and spider 19, however, the ratchet wheel 22 will be held against reverse rotation by the detent 23, while the pawl 24 will ride idly over the teeth of the ratchet wheel. This will permit the screw 26 to rotate relative to the ratchet wheel 22 and impart a downward movement to the screw. When the screw 26 reaches its lowermost position the ball 28 will register with a circumferential notch 40 so that further reciprocation of the spider 19 will not affect the vertical position of the screw. The threads of the screw 26 are rounded so that the ball 28 will yield when upward tension is exerted on the knob 41 at the top end of the screw. This makes it possible to return the plate 39 to its uppermost position by lifting the knob 41 with sufficient force to overcome the resistance of the ball 28.

A slice deflector 42 is secured to an upright post 43 which is swiveled in a bracket 44 connected to the chain box 45 of the slicing machine by cap screws 46. The inner edge of the deflector 42, as shown in Figs. 5 and 6, bears against the beveled face of the knife 13 closely adjacent the edge of the knife. The knives for slicing machines of this character are usually provided with a long bevel indicated at 47, Fig. 5, and a shorter bevel 48 adjacent the edge, the shorter bevel being formed by the grinding stones. The edge of the deflector 42 is preferably located just back of the circle which marks the conjunction of these two bevels. This leaves but a very narrow rim of the knife exposed so that the slices are not permitted to adhere to the surface of the knife as would sometimes otherwise occur. The deflector is yieldingly held in its operative position by a spring 49 secured to the bracket 44 by cap screws 50. This spring bears against a squared face of the post 43 and when outward force is exerted on the deflector 42 it may be swung away from the knife 13 and the spring 49 will engage the side 51 of the post 43 and hold the deflector in its open position, thus permitting cleaning of the knife and deflector. The deflector may be adjustably supported on the post 43 by screws 52 which extend through slots 53 in the deflector. Depressions are provided in the post 43 for receiving the spring 49 which thus holds the post from accidental displacement from its socket. To remove the deflector it is only necessary to press the spring 49 inwardly which will free the post and permit it to be lifted from its socket in the bracket 44. It will be seen from the drawings that the

operative face of the deflector is provided with corrugations forming an interrupted contact surface or limited contact lines for engaging the slices. The corrugations are provided with narrow edges forming substantially line contacts with the slices as they move away from the slicing knife. It will be noted that the deflector surface is of peculiar contour, the contact lines being directed generally outwardly and backwardly from the cutting edge of the knife. The lower lines are inclined slightly downwardly, but the inclination decreases with the lines spaced farther upwardly from the bottom of the deflector so that from midway of the deflector the contact lines are substantially horizontal. The backward inclination also decreases from the bottom of the deflector upwardly so that the deflector surface is curved outwardly, overhanging the bottom portion of the surface. From a point substantially on a horizontal line with the axis of the knife the rear ends of the deflector lines are arranged approximately in a vertical line, as indicated in Fig. 1. The particular shape has been determined after careful and extended experiments to produce a shape which will direct the slices into a horizontal position face down upon the receiving plate 39 as the slices are severed from the knife. The limited contact area is of great importance since any adherence of the slices to the deflector plate will distort the slice so that it will be crumpled up and will not be properly deposited upon the receiving plate. In other words, the deflector is such as to automatically effect uniform stacking of the slices upon the receiving plate immediately after being sliced.

A slice support 54 is arranged adjacent the edge of the reciprocating table 11 in position to support the projecting portion of the material which is severed by the knife 13 to form the slice. The support 54 is carried by a bracket 55 which is fastened to the top of the base 10 by screws 56. A projection 57 extends outwardly from the support 54 adjacent the cutting edge of the knife 13 in position to support the slice as it passes away from the cutting edge. A projection 58 is formed at the bottom edge of the deflector 42, the projection 58 being slightly below the top face of the support 54 and in position to receive the lower edge of the slice as it moves away from the projection 57. It is found desirable to have the projections 57 and 58 spaced a slight distance from each other to prevent any material which is drawn downwardly by the knife 13 from being held between the projections. The projections should be sufficiently close together, however, to form a substantially continuous support for the lower edge of the slice.

In operation, the plate 39 is raised to its uppermost position by means of the knob 41

and the meat or other material on the reciprocating table of the slicing machine is moved forwardly into position to be sliced by the knife 13. The machine is then operated to 5 reciprocate the table 11 and rotate the knife 13. As the slices are formed they are directed outwardly until the forward end of the slice assumes a substantially flat position and rests upon the surface of the plate 39. The 10 plate 39 is disposed downwardly from the top surface of the reciprocating table 11 a sufficient amount to permit the end of the slice to assume a substantially horizontal position where it comes in contact with the 15 plate 39. As the table 11 continues to move on its cutting stroke the formed portion of the slice is carried in the same direction by the movement of the plate 39 so that the slice is laid flat or substantially flat upon the 20 upper face of the plate 39. In order to straighten any wrinkles or folds that may be formed in the slice the plate 39 is caused to move at a slightly greater rate of speed than the reciprocating table 11. This will 25 be apparent from Fig. 2 which shows the point of connection between the rod 31 and the spider 19 as spaced inwardly from the periphery of the spider. This imparts a greater rate of speed to the periphery of the 30 spider than that of the point 32 and consequently a greater rate of speed than the reciprocating table. The pivot point 32 is located on the spider 19 in position to give a greater rate of speed at the time that the 35 slice is started than at other portions of the slicing movement. This is for the purpose of straightening out the front end of the slice which otherwise might be folded or wrinkled due to the fact that the forward end drops 40 downwardly some distance before it contacts with the surface of the plate 39. It will be noted from Fig. 2 that the curvature of the deflector 42 carries the end of the slice beyond the abutment plate 36 to insure that 45 the end of the slice will be directed onto the plate 39 within the inner side of the plate 36. After the first slice has been deposited upon the receiving plate 39 the table 11 and the spider 19 will be returned to their initial 50 position and at the same time the plate 39 will be fed downwardly. It will be noted that the screw 26 is comparatively steep and the amount of downward feed will be greater than the thickness of the slices formed. This 55 is desirable from the fact that the slices do not always lie perfectly flat and will occupy more space after they are sliced than when in the original piece. The plate 36 prevents the slices from being dislodged from the 60 outer edge of the plate 39 which would otherwise occur by centrifugal force. The end sections 37 and 38 are in position to hold the slices from sliding on the receiving table when the direction of reciprocation of the 65 receiving table is reversed. It will be seen

that the operation is such that the slices are directed downwardly and outwardly and are stacked directly on the receiving table as they are severed from the piece without the intervention of any moving carrier or transmitting device. The slices are stacked in position to be wrapped for the customer without the necessity of being handled and are therefore stacked automatically and yet the mechanism for stacking the slices is sufficiently 70 simple and inexpensive that the addition to the cost of the machine is small. 75

As shown in Fig. 5, the front face 60 of the post 43 is held by the spring 49 in a plane parallel to the beveled face 47 of the knife 13 so that when the deflector 42 is adjusted toward and away from the edge of the knife, the edge of the deflector will always remain close to the beveled surface of the knife. As the knife is worn away the deflector 42 is 80 adjusted backwardly away from the edge of the knife and the inclination of the face 60 of the post 43 will automatically move the deflector forwardly so as to compensate for the increased thickness of the knife 13 due 85 to the bevel 47. The slice support 54 is also adjustably held by the screws 56 so that it may be adjusted to a proper position relative to the cutting edge of the knife, thus maintaining the proper relation between the projections 57 and 58. 90

Since the slice receiver is positioned below the top surface of the meat table, the slices can fall free of relatively movable parts so that the stack of slices is not disarranged on 100 the return movement of the slice receiver. While it is desirable that the slice receiver be positioned below the meat table, it is not necessary that the whole receiver be so positioned but only that portion thereof that is 105 adjacent the table and upon which the slices are deposited.

As shown in Figs. 2 and 3, the abutment plate is closed at the side toward the knife by the portion 36 and closed at the sides by 110 the portions 37 and 38 leaving the side toward the operator unobstructed to permit easy access to the receiver for removing the slices and for cleaning the receiver. While the slice receiver illustrated is pivoted for oscillatory movement, it is essential only that the receiver be properly mounted for movement with the movable meat table, it being immaterial whether the receiver oscillates or reciprocates in a straight rectilinear path. 115

I claim:—

1. The combination with a slicing machine having a reciprocating table and a slicing knife of a slice receiver having a receiving 125 surface below the surface of said table adjacent said knife, means for moving said receiver simultaneously in the same direction with said table, and means for directing slices broad side down on top of one another 130

- on said surface directly as they are severed from a piece on said reciprocating table.
2. The combination with a slicing machine having a reciprocating table, of a knife for severing material from a piece supported on said table, a receiving table having its receiving surface disposed below the supporting surface of said reciprocating table, means for directing slices as they are severed from the piece on said reciprocating table directly onto the surface of said receiving table, and means for moving said receiving table to cause the slice to be extended over the surface thereof. 70
- 10 3. The combination with a slicing machine having a reciprocating table and a knife for severing slices from material on said reciprocating table, of a receiving table, means for directing slices onto said receiving table directly as they are severed from a piece on said reciprocating table, and means for adjusting said receiving table downwardly at intervals. 75
- 15 4. The combination with a slicing machine having a moving carriage and a knife for severing slices from material supported on said carriage, of a table for receiving the slices as they are severed, and means for moving said receiving table at a greater rate than said carriage so that slices deposited on said receiving table as they are severed will be drawn forwardly relative to said carriage to straighten any folds or wrinkles in the slices. 80
- 20 5. The combination with a slicing machine having a reciprocating work supporting carriage and a knife for severing slices from material supported on said carriage, of a receiving table having its receiving surface disposed below the surface of said work supporting carriage, means for directing slices broad side down directly from the material on said carriage to said receiving table, and means for moving said receiving table in the general direction of movement of said work supporting carriage and at a greater rate of speed than said work supporting carriage. 85
- 25 6. The combination with a slicing machine having a work supporting table, a slicing knife, and means for reciprocating said table to cause said knife to sever slices from material on said table, of a receiving table, means for directing slices onto said receiving table as they are severed from a piece on said work supporting table, means for moving said receiving table at a greater rate of speed than said work supporting table and in the same general direction as said work supporting table, and means for feeding said receiving table downwardly at intervals. 90
- 30 7. In combination, a slicing machine having a reciprocating work supporting table, a knife for severing slices from material on said table, a receiving table having its receiving surface disposed below the supporting surface of said work supporting table, means for moving said receiving table simultaneously with said work supporting table but at a greater rate of speed than said work supporting table, and means for feeding said receiving table downwardly at intervals. 95
- 35 8. In a slicing machine, a reciprocating table, a knife for severing slices from a piece carried by said table, a receiving table movable in an arc, means for directing slices from said reciprocating table onto said receiving table as they are formed by said knife, and means movable with said receiving table for preventing dislodgment of material from said receiving table by centrifugal force. 100
- 40 9. The combination with a slicing machine, of a receiving table movable in an arc, and an abutment on said receiving table and movable therewith for preventing slices from being discharged therefrom by centrifugal force. 105
- 45 10. The combination with a slicing machine, of a support for receiving material from said slicing machine, and an abutment for preventing material from being dislodged from said support, said support being movable vertically relative to said abutment. 110
- 50 11. The combination with a slicing machine having a reciprocating table, of a slice receiver comprising a receiving plate and an abutment having its upper edge adjacent the supporting surface of said reciprocating table, said receiving plate being disposed at the side of said abutment opposite said reciprocating table and below the upper edge of said abutment. 115
- 55 12. The combination with a slicing machine having a reciprocating table, of a receiving table having its outer edge disposed adjacent the edge of said reciprocating table, means for moving said receiving table simultaneously with said reciprocating table, and an abutment disposed adjacent the outer edge of said receiving table and having its upper edge disposed adjacent the supporting surface of said reciprocating table. 120
- 60 13. The combination with a slicing machine having a reciprocating table, of a knife for severing slices from material on said table, a receiving table having its outer edge disposed adjacent to but below the supporting surface of said reciprocating table, means for rotating said receiving table about an upright axis spaced outwardly from the edge of said reciprocating table, and an abutment disposed adjacent the outer edge of said receiving table and movable therewith for preventing displacement of material from said receiving table by centrifugal force. 125
- 65 14. The combination with a slicing machine having a reciprocating table and a knife for severing slices from material on said table, a receiving table movable in an arc, means for directing slices from said reciprocating table onto said receiving table as they are formed by said knife, and means movable with said receiving table for preventing dislodgment of material from said receiving table by centrifugal force. 130

- 5 said table, of a receiving table having its edge disposed adjacent the edge of said reciprocating table but lower than the supporting surface of said reciprocating table, means for oscillating said receiving table simultaneously with the movement of said reciprocating table, an abutment plate disposed about the outer periphery of said receiving table for preventing displacement 10 of slices from said receiving table by centrifugal force, and means for feeding said receiving table downwardly at intervals.
- 15 15. The combination with a slicing machine having a cutting knife and means for moving material relative to said knife to sever slices therefrom, of a deflector having a slice engaging face disposed at an angle to the cutting plane of said knife and having one edge of said face positioned adjacent 20 the cutting edge of said knife, said deflector face being formed to provide substantially line contact portions for engaging the slices at spaced intervals on the surface of said slices.
- 25 16. The combination with a slicing machine having a cutting knife and means for moving material relative to said knife to sever slices therefrom, of a deflector having a slice engaging face disposed at an angle 30 to the cutting plane of said knife and having one edge of said face positioned adjacent the cutting edge of said knife, said deflector face being formed to provide substantially line contact portions for engaging 35 the slice at spaced intervals on the surfaces of said slice, said line contact portions being arranged to extend substantially in the direction of movement of the slice.
- 40 17. The combination with a slicing machine having a slicing knife and means for moving material relative to said knife to sever slices therefrom, of a deflector having a slice engaging face disposed at an angle to the cutting plane of said knife, said deflector having contact ribs sloping downwardly and outwardly from the edge thereof adjacent the knife.
- 45 18. The combination with a slicing machine having a slicing knife and means for moving material relative to said knife to sever slices therefrom, of a deflector having a slice engaging face disposed at an angle to the cutting plane of said knife and having one edge thereof disposed adjacent the cutting edge of said knife, said deflector having slice engaging ribs on said face sloping downwardly and outwardly from said edge and having other ribs sloping outwardly from said edge but substantially horizontal.
- 55 19. The combination with a slicing machine having a slicing knife and means for moving material relative to said knife to sever slices therefrom, of a deflector having a slice engaging face disposed at an angle 60 to the cutting plane of said knife and having one edge of said face disposed adjacent the cutting edge of said knife, the edge of said face away from said knife having a substantially upright upper portion and a lower portion curved laterally in the direction of movement of the slices relative to said deflector to permit the upper portion of said face to overhang the lower portion thereof.
- 65 20. The combination with a slicing machine having a slicing knife and means for moving material relative to said knife to sever slices therefrom, of a deflector having a slice engaging face disposed at an angle to the cutting plane of said knife and having one edge of said face disposed adjacent the cutting edge of said knife, the lower portion of said slice engaging face being inclined at a lesser angle to the cutting plane of said knife than the upper portion thereof, said face having slice engaging ribs thereon, the ribs of the lower portion of said face being inclined downwardly from the edge of said face adjacent the cutting edge of said knife.
- 70 21. The combination with a slicing machine having a slicing knife and means for moving material relative to said knife to sever slices therefrom, of a deflector for directing slices away from said knife, said deflector having means thereon to support the lower edge of the severed portion of a slice.
- 75 22. The combination with a slicing machine having a slicing knife and means for moving material relative to said knife to sever slices therefrom, of a deflector for directing slices away from the face of said knife, said deflector having a ledge thereon in position to engage beneath the lower edge of the severed portion of a slice to support said edge as the slice is severed.
- 80 23. The combination with a slicing machine having a slicing knife and means for moving material relative to said knife to sever slices therefrom, of a deflector for directing slices away from said knife, means for supporting the lower edge of the slices as they are formed, the deflector being shaped to direct the upper edge of the slice outwardly to turn said slice broad side down.
- 85 24. The combination with a slicing machine having a slicing knife and means for moving material relative to said knife to sever slices therefrom, of a deflector for directing the slices away from said knife, said deflector having a slice engaging face shaped to direct the top edges of the slices outwardly and to turn said slices broad side down, and a slice receiver positioned below said deflector for receiving said slices in substantially horizontal position, said receiver being movable in the direction of movement of the slices as they are severed.
- 90 25. The combination with a slicing machine having a slicing knife and means movable relative to the cutting edge of said knife for presenting material to said knife to sever
- 95 100 105 110 115 120 125 130

- slices therefrom, of a deflector having a slice engaging face shaped to turn said slices broad side down as they are severed, a receiving table disposed below said deflector in position to receive the slices from said deflector, and means for moving said receiving table in the direction of movement of said slices but at a greater rate of speed than that imparted to said slices by said material moving means.
- 10 26. The combination with a slicing machine having a slicing knife and means movable relative to said knife for presenting material to said knife to sever slices therefrom, of a deflector for directing slices away from the face of said knife as they are severed, said deflector having a limited contact slice engaging face shaped to turn the top edges of the slices outwardly, means for supporting the severed portion of the lower edges of said slices, and a receiving table movable in the direction of movement of said slices as they are severed for receiving the slices from said deflector.
- 15 27. The combination with a slicing machine having a slicing knife and means movable relative to said knife for presenting material to said knife to sever slices therefrom, of a deflector having a limited contact slice engaging face shaped to direct the top edges of said slices outwardly, means for supporting the lower edges of said slices as they are severed, a slice receiving table movable about an upright axis in position to receive the slices from said deflector, and an abutment wall about the outer periphery of said table for preventing slices from being displaced by centrifugal force.
- 20 28. The combination with a slicing machine having a slicing knife and a reciprocating table for presenting material to said knife to be sliced, of a slice support disposed adjacent the cutting edge of said knife and having a projection thereon extending past said cutting edge at the side opposite said reciprocating table, and a deflector for directing slices away from said knife, said deflector having a projection thereon for receiving the lower edge of the slice after it passes from the projecting portion of said slice support.
- 25 29. The combination with a slicing machine having a slicing knife and a reciprocating table for presenting material to said knife to be sliced, of a slice support disposed adjacent the cutting edge of said knife and having a projection thereon extending past said cutting edge at the side opposite said reciprocating table, and a deflector for directing slices away from said knife, said deflector having a projection thereon for receiving the lower edge of the slice after it passes from the projecting portion of said slice support, said means being spaced from

15 prevent material from easily catching therebetween.

30. The combination with a slicing machine, of a slice receiver comprising a support having an upright arcuate peripheral wall, a slice support disposed within said wall and movable vertically relatively thereto, and means for moving said support downwardly as slices are deposited thereon.

31. The combination with a slicing machine, of a slice receiver comprising an upright arcuate wall, means for oscillating said receiver about the axis of said upright wall, said wall having an abutment portion at the end of the arcuate portion thereof for holding slices from displacement when the direction of movement of said receiver is reversed, and a supporting table disposed within the arcuate portion of said wall.

32. The combination with a slicing machine having a slicing knife and a reciprocating table for presenting material to said knife to sever slices therefrom, of a slice receiver having an upright arcuate wall movable about the axis thereof and past the cutting edge of said knife, the top edge of said wall being disposed adjacent the supporting surface of said reciprocating table, a slice receiving table disposed within said arcuate wall and below the upper edge thereof, and a deflector for directing slices into a recumbent position on said slice receiving table.

33. The combination with a slicing machine having a slicing knife and a reciprocating table for presenting material to said knife to sever slices therefrom, of a slice receiving table having its edge disposed adjacent the path of movement of said reciprocating table but below the supporting surface of said reciprocating table, means for moving said slice receiving table simultaneously with the movement of said reciprocating table but at a greater rate of speed, an abutment for preventing centrifugal displacement of slices from said slice receiving table, said abutment being constrained to move in unison with said slice receiving table, and a deflector for directing slices as they are severed onto said slice receiving table.

34. The combination with a slicing knife, of a substance support, a slice receiver arranged adjacent the cutting edge of said knife and in a plane spaced from the supporting surface of said substance support, and a deflector for directing slices as they are severed onto said slice receiver, said deflector being arranged to extend away from the cutting edge of said knife past the outer edge of said receiver.

35. The combination with a slicing knife, of a carriage for presenting material to said knife to sever slices therefrom, a receiver having an arcuate abutment plate disposed about the outer edge thereof, means for moving said receiver simultaneously with said

carriage and in the same direction, and a deflector for directing slices away from said knife, said deflector being positioned above the top of said abutment plate and extending to a position within the arc formed by said abutment plate for directing slices from said knife onto said receiver.

36. The combination with a slicing knife, of a carriage for moving past said knife to sever slices therefrom, a slice support having a projection thereon extending beyond the cutting plane of said knife at the side opposite said carriage, a receiver having an abutment plate disposed about the outer periphery thereof, the upper edge of said abutment plate being below the supporting surface of said slice support, and a deflector for directing slices away from said slicing knife and past said abutment plate onto said receiver.

37. The combination with a slicing knife, of a slice support disposed adjacent the cutting edge of said knife and having a projection thereon extending past said cutting edge, a deflector having a projection thereon in position to receive slices from the projection on said slice support, means for supporting said slice support for adjustment in the direction of the cutting plane of said knife, and means for supporting said deflector for adjustment toward and away from the projection on said slice support.

38. The combination with a slicing machine having a slicing knife and a substance supporting table, of a slice receiver having its slice receiving surface positioned substantially parallel with said substance supporting table below the surface of said table adjacent the cutting edge of said knife, and a deflector acting as a stacker for directing the slices broad side down onto said receiving surface directly from the piece as they are sliced, said deflector stacking the slices uniformly on said receiving surface.

39. The combination with a slicing machine having a slicing knife and a work supporting table movable past the edge of said knife, of a slice receiver, means for moving said receiver with said table, and an abutment on said slice receiver to prevent dislodgment of the slices thereon, said abutment extending partially around said receiver leaving the operator's side thereof unobstructed to permit easy access to said receiver.

40. The combination with a slicing machine having a slicing knife and a work supporting table movable past the edge of said knife, of a rotatably mounted slice receiver movable with said table, and an abutment on said slice receiver to prevent dislodgment of the slices thereon, said abutment extending partially around said receiver leaving the operator's side thereof unobstructed to permit easy access to said receiver.

41. A slicing machine comprising a slicing knife, a work supporting table movable past

the edge of said knife, a slice receiver, means for moving said receiver in timed relation to the movement of said table, and an abutment adapted to move with said slice receiver, said abutment being of sufficient height to prevent dislodgment of each and every slice deposited thereon.

42. In a slicing machine, the combination with a slicing knife, of means for moving material relative to said knife to sever slices therefrom, and a deflector for said slices having means thereon for preventing distortion of the slices as they contact with said deflector, said last-mentioned means comprising relatively restricted contact portions arranged on the slice engaging surface of said deflector, said contact portions being adapted to contact with said slices during substantially the entire movement of said slices over the surface of said deflector.

43. In a slicing machine, the combination with a slicing knife, of means for moving material relative to said knife, and a deflector for the slices formed by said knife, said deflector having means thereon for preventing any substantial resistance to the movement of the slices thereover so as to prevent buckling of the slices, said last-mentioned means comprising a plurality of relatively restricted contact surfaces extending in substantially the direction in which the slices move over the surface of said deflector, said contact surfaces being adapted to contact with said slices during substantially the entire period of engagement of each slice with said deflector.

44. In a slicing machine, the combination with a slicing knife, of means for moving material relative to said knife to sever slices therefrom, a deflector having a contact face disposed at an angle to the cutting plane of said knife, and means on said deflector for preventing slices from adhering to said face comprising relatively narrow contact portions on said face extending in substantially the direction in which the slices move over said face, said contact portions contacting with the slices during substantially the entire period of movement of each slice over the face of said deflector.

45. In a slicing machine, the combination with a slicing knife, of means for moving material relative to said knife to sever slices therefrom, and a deflector for said slices having an interrupted contact surface to prevent said slices from adhering to said deflector, said interrupted contact surface comprising a plurality of projections for supporting the slices in spaced relation to the body portion of the deflector, said projections forming a support for the slices during substantially the entire period during which the slices are in contact with said deflector, said projections being arranged so that the path of movement of a slice over the surface of the deflector is

gradually varied so as to change its position relative to the cutting plane of the knife.

46. In a slicing machine, the combination with a reciprocating table, of a slicing knife, a slice receiver having its receiving surface positioned substantially perpendicular with the cutting plane of said knife and below and adjacent to the material supporting surface of said reciprocating table for receiving slices directly as they are cut, a deflector acting as a stacker for depositing slices directly onto said receiving surface as they are cut, and means for moving said slice receiver simultaneously with said reciprocating table past the cutting edge of said knife, said deflector stacking said slices in regular order on said receiving surface.

47. In a slicing machine, the combination with a slicing knife, of a work supporting table movable past the edge of said knife, a slice receiver, means for moving said receiver in timed relation with the movement of said table toward said slicing knife, and an abutment on said slice receiver to prevent dislodgment of the slices on said receiver, said abutment being of sufficient height to prevent the dislodgment of each slice after it is stacked on said table.

48. In a slicing machine, the combination with a slicing knife, of a work supporting table movable past the edge of said knife, a rotatably mounted slice receiver movable with said table, and an abutment on said slice receiver of sufficient height to prevent dislodgment of all slices stacked on said receiver.

49. A slicing machine comprising a slicing knife, and a deflector for deflecting slices away from said knife after said slices are cut from a substance by said slicing knife, said deflector having grooves in the surface thereof extending in substantially the same direction as the path of movement of said slices during their movement away from said knife, said grooves forming raised portions therebetween for reducing the resistance offered by said deflector to the movement of said slices over the surface of said deflector, said raised portions contacting with said slices during substantially the entire movement of said slices over the surface of said deflector.

50. In a slicing machine, the combination with a slicing knife, of a substance supporting table movable past said slicing knife, a slice receiver having its receiving surface positioned to receive slices directly from said knife after said slices have been cut from a substance on said supporting table, and a deflector acting as a stacker for directing the slices broad side down onto said receiving surface directly from the edge of said knife as said slices are cut from said substance, said deflector forming the sole means for stacking said slices on said receiving surface.

51. A slicing machine comprising a recip-

rocating table, of a knife for cutting slices from a substance supported on said table, a slice receiver having a receiving surface below the surface of said table adjacent said knife, means for moving said receiver simultaneously and in the same direction as said table while the slices are being cut, and an abutment on said receiver for preventing the slices from being dislodged from said receiver.

52. In a slicing machine, the combination with a slicing knife, of means for moving material relative to said knife to sever slices therefrom, and a deflector for said slices having means thereon for preventing substantial distortion of said slices as they contact with said deflector, said last-mentioned means comprising relatively restricted contact portions arranged on the slice-engaging surface of said deflector and in proximity to the forward edge of said slice deflector to thereby reduce the resistance offered by the deflector to the movement of the slice thereover.

53. In a slicing machine, the combination with a slicing knife, of means for moving material relative to said knife to sever slices therefrom, and a deflector for deflecting slices away from said knife comprising a slice deflector having a plurality of spaced ribs arranged adjacent the forward edge of said deflector and extending substantially in the direction of the movement of said slices over the surface of said deflector.

54. The combination with a slicing machine having a slicing knife and a reciprocating table for presenting material to said knife to be sliced, of a slice receiver mounted adjacent the cutting edge of said knife and having its receiving surface disposed below the surface of said reciprocating table, said receiver having a flange thereon, the top edge of said flange being above the surface of said receiver but not above the surface of said reciprocating table.

In testimony whereof I have signed my name to this specification on this 11th day of July, A. D. 1926.

JOSEPH FOLK.
